FIG. 4.

UNITED STATES PATENT OFFICE.

CLAUDE R. NOBLES, OF ST. JOHN, NEW BRUNSWICK, CANADA.

SASH-HOLDER.

1,157,797.

Specification of Letters Patent.

Patented Oct. 26, 1915.

Application filed November 27, 1914. Serial No. 874,283.

To all whom it may concern:

Be it known that I, CLAUDE R. NOBLES, a subject of the King of Great Britain, residing at St. John, New Brunswick, Canada, have invented certain new and useful Improvements in Sash-Holders, of which the following is a specification.

This invention relates to sash holders, and has for its object to provide certain new and useful improvements in this class of devices whereby a window sash may be conveniently held at any desired elevation, and also conveniently released to permit of the window being raised or lowered.

It is a further object of the invention to provide a simple and inexpensive device which can be readily applied to a window sash without making any alterations therein beyond recessing one of the stiles of the sash so as to accommodate the parts of the holder. The holder may be fitted to any ordinary window sash without requiring the employment of a skilled workman.

With these and other objects in view, the present invention consists in the combination and arrangement of parts as will be hereinafter more fully described, shown in the accompanying drawing and particularly pointed out in the appended claim, it being understood that changes in the form, proportion, size and minor details may be made, within the scope of the claim, without departing from the spirit or sacrificing any of the advantages of the invention.

In the drawings:—Figure 1 is a front elevation of the lower portion of a window equipped with a sash holder of the present invention. Fig. 2 is an enlarged fragmentary view showing the recess in the window sash and the wedging or holding element in one of the recesses. Fig. 3 is an elevation looking at the edge of the window sash with the holder in place and in condition for lifting the sash. Fig. 4 is a cross-sectional view on the line 4—4 of Fig. 5. Fig. 5 is a view similar to Fig. 3 with the parts in the positions assumed in the closed position of the window.

Like characters of reference designate corresponding parts in each of the figures of the drawing.

For the purpose of illustrating the application and operation of the present invention there have been shown in the accompanying drawing a window frame 1 and a window sash 2.

In one of the stiles of the sash, and preferably near the bottom thereof, there is cut or otherwise formed a recess 3, preferably rectangular in shape and of suitable proportions. This recess is formed in the inner face of the sash so as to be accessible from the interior of the building, and said recess intersects that edge of the sash which is adjacent the window frame, as will be clearly understood by reference to Fig. 4 of the drawing. The back of the recess 3 is also recessed to form a seat 4, which seat intersects the edge of the sash. The greatest transverse width of the seat 4 is at its middle, from which the width of the seat decreases regularly in opposite directions toward its ends. Preferably the seat 4 is segmental in shape and its wall 5 being an arc of a circle. If desired, the wall 5 may be provided with a suitable lining 6, such, for instance, as rubber, felt, or the like. Within the seat 4 is a wedge element 7, preferably a hard spherical body or ball, the diameter of which is greater than the greatest width of the seat 4 at its middle, so as to project slightly through the open side of the seat.

Located in the recess 3 is a slide 8, preferably in the form of a rectangular metallic plate which is shorter than the recess and capable of sliding endwise therein. This plate has the same width as the recess 3 and is provided with an upper pin 9 and a lower pin 10 working in the seat 4, one above and one below the wedging member 7, and designed to move the wedging member in the seat as will be hereinafter explained.

For the purpose of holding the slide 8 in place, there is a face plate 11 countersunk in the face of the stile of the sash and fixed in place by means of suitable fastenings 12. This face plate is provided with a longitudinal slot 13 through which projects the shank 14, carried by the slide 8, and in turn carrying at its outer end a knob or handle 15.

In the closed position of the window, the wedging member 7 will be at the middle of the seat 4 and will be supported by engagement with the back of the seat and the adjacent edge of the window frame. Any attempt to lift the window from the exterior of the building will result in a wedging of the member 7 and thereby prevent unauthorized opening of the window. To open the window from the interior of the building, the knob or handle 15 is grasped and

pushed upwardly, whereby the lower pin 10 will lift the wedging member 7 into the widest middle portion of the seat 4, and thereafter the window may be opened by 5 pushing upwardly upon the knob or handle 15 as the shank thereof will be at the upper end of the slot 13. With the window sash in an elevated position, if the handle or knob 15 is released, the sash will move 10 downwardly a short distance until the wedging member 7 has become wedged between the back wall of the seat 4, and the adjacent edge of the window frame. To lower the sash, the knob or handle 5 is pulled down- 15 wardly so as to push the wedging member 7 into the middle widest portion of the seat so as to free the sash and permit of it being moved freely downward.

With the window sash in its lowermost 20 position, the wedge member 7 will be at the middle of the seat or recess 4 because it will be supported by reason of its engagement with the back of the recess and the adjacent edge of the window frame. The slide 8 will 25 also be at its lowermost position with the pin 9 at the top of the wedge 7 and the pin 10 in engagement with the back of the seat or recess 4. When the handle 15 is manipulated to lift the window sash, the slide 8 will move upwardly until the shank 14 30 strikes the upper end of the slot 13, and the upper end of the slide strikes the upper end of the recess 3, whereby the movement of the slide is limited, and the lower pin 10 35 will be in engagement with the bottom of the wedge and the upper pin 9 in engagement with the back of the seat 4. In other words, the length of the slide 8 and the length of the recess 3 are proportioned to 40 properly limit the endwise play of the slide 8, and the pins 9 and 10 are located upon the slide in proper positions to respectively bring the wedge into the middle portion of the seat 4.

45 As best shown in Fig. 4 of the drawings, the window frame is provided with a strip

16 of felt, rubber, metal or other material, which is preferably set into the frame in a position to be engaged by the wedge member 7. The wedge element 7 has been described as a hard spherical body or ball. However, as a hard element will dent or otherwise mar the window frame, I contemplate making the member of rubber or other suitable material having sufficient 55 elasticity to produce the desired effect without injuring the window frame.

While the invention has been described in connection with a window sash, it is to be understood that it also may be used in connection with elevators, draws, sliding and swinging doors, fanlights, rolling desk tops, etc.

Having thus described the invention, what is claimed and desired to be secured by Letters Patent, is:

The combination of a window sash having a seat formed in one of the stiles thereof, that side of the seat adjacent the window frame being open, and the opposite side of 70 the seat being inclined in opposite directions from its middle toward the ends of the seat, a wedging member in the seat and having a width exceeding the greatest width of the seat whereby the member is in constant 75 engagement with the seat and window frame, and a slide mounted upon the stile and provided with upper and lower projections lying at opposite sides of the wedging member for contact therewith to move 80 said wedging member in opposite directions into the widest portion of the seat, said projections being spaced to an extent greater than the diameter of the wedging member whereby to permit movement of the wedging 85 member between the projections.

In testimony whereof I affix my signature in presence of two witnesses.

CLAUDE R. NOBLES.
